MANUFACTURE OF SAFETY GLASS

Cyril Wilfred Bonnicksen, Slough, England, assignor to Protectoglass Limited, London, England, a British company

Application September 23, 1933, Serial No. 690,759
In Great Britain June 4, 1932

10 Claims. (Cl. 49—81)

This invention comprises improvements in or relating to the manufacture of safety glass.

It is an object of the invention to provide means for facilitating the assembly and manufacture of safety glass in accordance with prior United States specification Serial No. 627,502.

In the said application there is described a process for the manufacture of safety glass in which sheets of glass covered with a cellulosic material (for example celluloid) are immersed in a laminating bath of a high boiling point liquid which is a softener or plasticizer for celluloid and are brought together while in said bath under a light pressure, and are maintained together in the bath until the layers of celluloid upon the glass have become united together.

The present invention comprises in apparatus for the manufacture of safety glass the combination of a laminating bath, a vertically movable cradle to receive sheets of glass coated with cellulosic material face to face and hold them in a non-horizontal position and means for lowering the cradle gradually into the liquid.

By this means the introduction of the sheets without disturbance or air bubbles is greatly facilitated.

By disposing the sheets in a vertical or nearly vertical position as above described the exposed surface of liquid in the bath is reduced to a minimum and the possibility of contamination of this surface by extraneous impurities is minimized with the result that the bath can be used for a longer period before changing the liquid than is the case if the sheets are introduced into it horizontally or nearly horizontally.

Preferably the cradle is such as to hold the glass sheets in a nearly vertical position and the direction of its movement into the liquid bath is approximately vertical.

The cradle may co-operate with a leaf or leaves between which and itself the glass sheets are located. The parts of the leaves which press upon the glass sheets are preferably yieldingly mounted so as to equalize the pressure on the glass at all points. This may be effected by providing the leaves with yielding studs distributed over their glass-engaging surfaces.

The invention further relates to various constructional features as hereinafter described.

One specific construction in accordance with the invention will now be described by way of example, reference being had to the accompanying drawings in which—

Figure 1 is a front elevation of a laminating

bath, parts being broken away to show the internal construction;

Figure 2 is a vertical section on the line 2—2 of Figure 1;

Figure 3 is a detail;

Figure 4 shows a collapsible bracket upon a cradle;

Figure 5 is a horizontal section on the line 5—5 of Figure 4, and

Figure 6 is a diagram of the fluid pressure control apparatus.

The bath consists of a deep rectangular tank 11 narrow from front to back but of sufficient depth to accommodate the full width of the glass sheets which are to be combined together into 15 safety glass. The sides taper outwards slightly towards the top as seen in Figure 2.

The tank 11 is made of galvanized iron and screwed to a stout wooden backing 12. Secured to the back of the tank are four brass grids 13 20 provided with fixing lugs 14 by which they are held in place. The parts are broken away so that the second grid from the left in Figure 1 can be seen in its entirety but only the tops of the other grids are visible in the figure. The 25 side edges 15 of these grids are machined to a V-formation and are carefully disposed so as to be parallel to one another. They serve to guide between them three cradle sections 16 which are also cast in the form of grids and 30 two of which are shown in situ in Figure 1 while the third or left hand cradle section has been removed. Each cradle section is provided with grooved running wheels 17 which run upon the V-guides 15 of the grids 13. The cradle 35 sections are united together along their top edges by a galvanized steel channel member 18 and a backing plate 19. At the centre the channel member 18 is hung from a rod 20 depending from an operating cylinder 21 as best seen in 40 Figure 6. The stroke of the operating cylinder is such that the cradle formed by the three sections 16 can be fully lowered into the bath 11 until it reaches the bottom position as shown in Figures 1 and 2 or fully raised until the whole 45 of the grid portion is exposed above the surface of the liquid in the bath 11.

Near the bottom of each cradle section there are secured to it bracket arms 22 which project forwardly from the cradle and then upwardly 50 in a direction slightly divergent from the face of the cradle. Moreover, additional folding brackets 23, 24, 25 are provided at the sides of the cradle at higher levels than the main bracket 22. The construction of the folding brackets 55

can be seen in Figures 4 and 5 which illustrate the uppermost bracket 25. As will be seen, each side of the cradle section 16 is cast with a longitudinal recess 26 on the side of which are two pivoted pins 27, 28. To the two pins are pivoted two parallel links 29, 30 and the links are pivoted at 31, 32 to the bracket arm 25. Below the links 29, 30 when in the position shown in the drawings is a lug 33 which supports the weight. It will be seen that the bracket arm can be swung up about the links into the chain line position in Figure 4, where it is out of the way behind the surface of the cradle section 16. The brackets 22, 23, 24, 25 are provided for the purpose of supporting sheets of glass and the folding brackets serve to support small sheets when the cradle is not required for larger sheets. If large sheets are to be supported then the folding brackets are moved into the position shown in chain lines in Figure 4 so as not to interfere with the glass on the cradle.

The surface of the cradle section 16 and also the surface of the grids 13 which alternate with them on the back of the tank 11 are studded with spring plungers 34 disposed at uniform distances apart for the purpose of exerting a gentle spring pressure over the whole area of a piece of glass held in the cradle during the operations hereinafter described. A detail of the construction of one of the plungers, which are all alike, is shown in Figure 3 and it will be seen that they comprise a stem 35 at the back of the plunger proper, which stem passes through a hole in the cradle 16 or grid 13 as the case may be and is secured at the back by a split pin 36. Behind the head of the plunger 34 is a spring 37.

Within the laminating bath and close to the bottom thereof are a series of brackets 40 which support a rockshaft 41. Upon the rockshaft 41 there are pivoted a series of swinging grids 42 which each lie opposite one of the grids 13 or cradle sections 16. The swinging grids or leaves are provided with spring plungers 43 similar to the spring plungers 34 and they are adapted, when swung towards the cradles, to press upon the back of a compound glass sheet laid on the cradles to hold it under spring pressure in the laminating bath. The swinging grids, of which only two are fully seen in Figure 1, others being broken away or hidden by the front of the bath, are all united together by a galvanized steel bar 44 along their top edges and the bar 44 is connected by links 45 to rams 46 of operating cylinders 47. In Figure 6 the swinging frame operating cylinders 47 are shown but not their connections to the frame.

In addition to the parts described there are suitable control elements the construction of which forms no part of the present invention but which are shown in Figure 6 in order to illustrate the preferred manner of carrying the invention into effect. These include a hand-operated control valve 49 and a rotary valve 50 which is actuated by the rod 20 of the lifting cylinder 21. Only one of the cylinders 47 which operate to close the folding leaves 42 against the cradle 16 is shown in Figure 6, this cylinder being a double-acting cylinder provided with a pipe connection 51 connected to the back end of the cylinder, supply of pressure to which holds the leaves open and a pipe connection 52 connected to the front end of the cylinder, supply of pressure to which serves to close the leaves. The branches 53, 54 are connected

to the other cylinders and operated simultaneously. Air is supplied to the pipes 52, 54 through a branch 55 from a main supply 56 and tends continuously to close the leaves, but when air at the same pressure is supplied through the branches 51, 53 to the backs of the cylinders 47 the leaves are held open because of the larger area of the back of the piston in the cylinder 47 compared with the area at the front of the piston, which is reduced by the ram 46. The main air supply pipe 56 goes to the operating valve 49 and when the handle 57 of this valve is in the position shown in the drawings air passes to the pipe 58 and thence through the shuttle valve 59 and pipe 60 to the pipes 51, 53, 15 thus holding the leaves open. The shuttle valve 59 consists simply of a small piston-shaped valve located in a cylindrical casing and capable of being pushed by the air pressure either to the right or left hand end of the casing as the case 20 may be. The air supply through the pipe 58 pushes the shuttle valve to the left-hand end of the casing 59 in the conditions supposed in Figure 6.

A branch 61 from the pipe 58 enters a direction relay valve 62 which contains a shuttle member 63. The shuttle 63 is pushed over to the right in the figure by the pressure and admits air to the pipe 64 which carries it through a ball of a non-return valve 66 to the underside 30 of the cylinder 21 which controls the cradle. In the position of the parts shown in the drawings the piston of the cylinder 21 has therefore been slowly raised to its uppermost position and the cradle is therefore lifted out of the laminat- 35

In this position of the parts the operator can lay upon the brackets carried by the cradle sheets of glass in pairs, which have been coated upon one face with celluloid or other cellulosic 40 material, the celluloioded faces of the glass sheets being towards one another. Upon moving the handle 57 over to the position indicated by the chain line 67 in Figure 6 the pipe 58 is connected to the atmosphere by the valve 49 through the exhaust pipe 68 and the air pressure in pipe 56 is connected to the pipe 69 which passes to the rotary valve 50. The rotary valve 50 is controlled by a lever 70 having a forked end which lies in the path of a pin 71 on the rod 50 20 of the cradle cylinder 21. In the position of the parts shown in the drawings the pipe 69 will be connected by the valve 50 to the pipe 72 connected to the shuttle valve 59. The pipe 58 being now connected to the atmosphere by the valve 49 the pressure in the pipe 72 will force the shuttle of valve 59 to the right hand position of Figure 6 and thus pressure will be admitted from the pipe 72 to the pipe 60. This happens instantaneously upon the lever 57 of the valve 60 49 being moved into the position 67 and thus although the pipe 58 is now connected to the atmosphere pressure is maintained in the pipe 60 and the cylinders 47 are held with the leaves 42 open. Owing to the action of the bleed valve 65 air slowly leaks out of the cylinder 21 through the pipe 64, direction relay valve 62 and branch 61 to pipe 58 and thus to the atmosphere. The cradle 16, therefore, is lowered slowly into the laminating bath at a rate determined by the bleed valve 65 and the glass becomes gradually immersed edgewise in the liquid in the laminating bath. Owing to the smoothness of this motion no air bubbles are occluded with the glass sheets and the celluloid becomes

gradually immersed in the softening liquid which constitutes the laminating bath. The operator in laying the glass sheets on the brackets 22 takes care to leave a slight space between the opposed faces of the glass at the bottom and this ensures free entry of the softening liquid between the celluloid faces.

When the cradle reaches almost its bottom position the pin 71 engages the slot in the lever 10 70 of the rotary valve 50 and during the final movement of the cradle to the bottom the lever 70 is swung over into the chain-line position 73 (Figure 6). In this position the pipe 72 is connected by the valve 50 to the exhaust pipe 14 and the pressure in the conduits 51, 53 therefore falls to that of the atmosphere. Consequently the air pressure in pipes 52, 54 is able to push over the pistons in cylinders 47 and the leaves 42 are closed against the cradles 16 and grids 13 bringing the glass sheets between them gently together under the spring pressure of the plungers 43. The amount of this spring pressure is only of the order of a few ounces per square inch and under this gentle pressure the celluloided faces of 25 the glass are brought together while excess softening liquid is extruded.

At the same time that the lever 70 opens the conduit 72 to the atmosphere it connects the conduits 69 to a conduit 75 which is connected through an adjustable bleed valve 76 and a conduit 77 to a reservoir 78 which will be herein referred to as the time delay reservoir. From the pipe 77 a branch 79 proceeds to the direction relay valve 62 and presses upon the opposite side 30 of the shuttle valve 63 therein from that to which the branch 61 is connected. As the branch 61 is now connected through the pipe 58 to the atmosphere, as soon as a small pressure is built up in the branch 79 the shuttle valve 63 moves over and seals the conduit 64 from the conduit 61. No further motion of the parts takes place until the pressure in the time delay reservoir 35 78 has risen to an adequate predetermined value. This cannot take place immediately because the air passes only slowly through the adjustable bleed valve 76 and the bleed valve is adjusted to allow the predetermined pressure to be reached only after the time required to ensure the union of the celluloided interfaces.

50 A resetting cylinder 80 is provided which is connected by a piston rod 81 and connecting rod 82 to the handle 57 of the valve 49. Pressure adequate to operate the resetting cylinder 80 will restore the valve 57 to the position shown in Figure 6. The resetting cylinder 80 is supplied with air under pressure at the appropriate time by a conduit 83 connected through a valve 84 and pipe 85 to the time delay reservoir 78.

The valve 84 is held on its seat by a spring 60 and is adjusted to lift when the pressure in the time delay reservoir reaches a predetermined value. When the pressure in the reservoir 78 has built up to a figure sufficient to pass the setting of valve 84 air is admitted to the resetting cylinder 80 and the valve 49 is restored to the position shown in Figure 6. The effect of this is to admit air under pressure to the pipe 58, to throw over the shuttle valve 59 and supply air under pressure through the conduit 60 to the branches 51, 53 of the cylinders 47 which operate the leaves 42. Thus the glass is unclamped. Simultaneously the air under pressure passes into the conduit 61 but the direction relay valve 62 does not move over to the right into the position shown in dotted lines in Figure 6 until the

pressure in the time delay reservoir 78 has fallen to a certain extent. The pressure in the time delay reservoir begins to fall immediately the valve 49 has been reset by the cylinder 80 as already described because the conduit 75 is connected through the valve 50 and conduit 69 to the atmosphere, but the delay in movement of the direction relay valve 62 suffices to ensure that the cylinders 47 can open the leaves and free the glass from pressure before the cylinder 24 receives air through conduits 61, 64 to lift the cradle. Thus the glass is first unclamped and then the cradle lifted. In rising the cradle moves the lever 10 back into its uppermost position and the parts resume the position shown in Figure 6 in which the glass can be removed from the elevated cradle and fresh glass placed in position for a new cycle of operations.

The softening liquid employed in this bath which may be any desired and suitable liquid is referred to in prior United States specification Serial No. 627,502. It will be observed that the apparatus acts automatically to maintain the glass immersed for a predetermined time and then to remove it from the bath, no attention being required from the operator from the time when he moves the handle till he removes the glass from the machine.

I claim:—

1. Apparatus for the manufacture of safety glass comprising a laminating bath, a vertically movable cradle to receive sheets of glass having an interposed mass of plastic material and to hold them in a non-horizontal position, means for lowering the cradle gradually into the liquid bath, and a leaf arranged for cooperation with the cradle and between which the glass sheets are located, which leaf is movably mounted so that it may be caused to approach the cradle after immersion of the glass and press the glass sheets together.

2. Apparatus for the manufacture of safety glass comprising a laminating bath, a vertically movable cradle to receive sheets of glass having an interposed mass of plastic material and to hold them in a non-horizontal position, means for lowering the cradle gradually into the liquid bath, and a leaf arranged for cooperation with the cradle and between which the glass sheets are located, which leaf is movably mounted so that it may be caused to approach the cradle after immersion of the glass and press the glass sheets together, the parts of the leaf which press upon the glass being yieldingly mounted.

3. Apparatus for the manufacture of safety glass comprising a laminating bath, a vertically movable cradle to receive sheets of glass having an interposed mass of plastic material and to hold them in a non-horizontal position, means for lowering the cradle gradually into the liquid bath, and a leaf arranged for cooperation with the cradle and between which the glass sheets are located, which leaf is movably mounted so that it may be caused to approach the cradle after immersion of the glass and press the glass sheets together, said leaf having yielding studs distributed over its glass engaging surface.

4. Apparatus for the manufacture of safety glass comprising a laminating bath, a vertically movable vertical cradle to receive sheets of glass having an interposed mass of plastic material and to hold them in a non-horizontal position, vertically spaced apart folding brackets on said cradle, means for lowering the cradle gradually into the liquid, upstanding slides in the lami-

nating bath whereon the cradle is movably supported, said means for raising and lowering the cradle comprising a vertical cylinder and piston above the slides.

5. Apparatus for the manufacture of safety glass comprising a laminating bath, a vertically movable cradle to receive sheets of glass having an interposed mass of plastic material and to hold them in a non-horizontal position, means for lowering the cradle gradually into the liquid, upstanding slides in the laminating bath whereon the cradle is movably supported, said means for raising and lowering the cradle comprising a vertical cylinder and piston above the slides, 10 said cradle having brackets thereon located above the level of the bottom of the cradle and so movable as to be capable of being set outstanding from the faces of the grid to support the glass sheets and of being retracted behind the glass supporting face of the grid to allow 15 room for the support of larger pieces of glass at a lower level on the cradle.

6. Apparatus for the manufacture of safety glass comprising a laminating bath, a vertically movable cradle to receive sheets of glass having an interposed mass of plastic material and to hold them in a non-horizontal position, means for lowering the cradle gradually into the liquid bath, a hinged grid pivoted along its 20 lower edge in the laminating bath, and fluid-pressure means for causing the hinged grid to be pressed toward the cradle.

7. Apparatus for the manufacture of safety glass comprising a laminating bath, a vertically movable cradle to receive sheets of glass having an interposed mass of plastic material and to hold them in a non-horizontal position, means for lowering the cradle gradually into the liquid bath, a hinged grid pivoted along its lower edge 25 in the laminating bath, fluid-pressure means for causing the hinged grid to be pressed toward the cradle, and means to insure that the vertically movable cradle may only be lowered into

the bath at such time that the hinged grid is retracted and the hinged grid may only be advanced at such time as the cradle has been fully lowered into the bath.

8. Apparatus for the manufacture of safety glass comprising a laminating bath, a vertically movable cradle to receive sheets of glass having an interposed mass of plastic material and to hold them in a non-horizontal position, means for lowering the cradle gradually into the liquid 10 bath and for raising it therefrom, slides in the laminating bath, said cradle constituting a grid movably supported upon said slides, and retractable vertically spaced apart brackets on said cradle.

9. Apparatus for the manufacture of safety glass comprising a laminating bath, a vertically movable cradle to receive sheets of glass having an interposed mass of plastic material and to hold them in a non-horizontal position, means 20 for lowering the cradle into the bath, upstanding slides in the bath whereon the cradle is movably supported, said means for raising and lowering the cradle comprising a vertical cylinder and piston above the cradle, said cradle being in the form of a grid and having thereon a plurality of vertically spaced apart brackets outstanding from the face thereof whereby the 25 glass sheets are supported.

10. Apparatus for the manufacture of safety 30 glass comprising a laminating bath, a vertically movable cradle having a plurality of vertically spaced apart brackets thereon to receive sheets of glass having an interposed layer of plastic material, means for lowering the cradle into the 35 liquid, means for transposing the sheets from a position where they are separated to a position of actual contact, and means for exerting a uniform pressure over the whole area of a piece of glass held in the cradle while in the 40 bath, said last-mentioned means comprising a series of spring-backed plungers.

CYRIL WILFRED BONNIKSEN.
